UNITED STATES PATENT OFFICE

2,410,581

HYDRAULIC PRESS

Relza J. Hess and Frank G. Cizek, Chicago, Ill.,
assignors to American Steel Foundries, Chicago,
Ill., a corporation of New Jersey

Original application September 13, 1943, Serial
No. 502,124. Divided and this application May
15, 1944, Serial No. 535,620

12 Claims. (Cl. 18—16)

1

Our invention relates to presses and more particularly to an hydraulic slugging or briquetting press for compressing material into a "slug" or "brick" for manufacturing use. The subject matter of the present application is divided out of a copending application Serial No. 502,124, filed September 13, 1943, in the United States Patent Office in the joint names of Relza J. Hess and Frank G. Cizek, for Hydraulic press.

The general object of the present invention is to design a press in which means is utilized for adjusting the stroke of the main ram which reciprocates within the material cylinder of the press. By this means the head of the main ram is positioned at a predetermined point within the material cylinder, thus predetermining the amount of material which may be inserted therein preparatory to a slugging or briquetting operation.

A more specific object of our invention is the provision of novel hydraulic means for adjusting or controlling the stroke of the main ram as above described. Our invention comprehends an arrangement in which an auxiliary ram extends into the main ram cylinder and abuts the adjacent extremity of the main ram, said auxiliary ram being reciprocal within an auxiliary cylinder to which hydraulic fluid is supplied under pressure for the purpose of adjusting the initial position of the main ram within the main ram cylinder and thereby limiting the stroke of the main ram for the purposes above described.

In the drawing:

Figure 1 is a side elevation, partially in section, of the upper half of a press embodying our invention, and Figure 2 is a side elevation, partly in section, showing the lower half of said press, in combination with a hydraulic circuit for actuating the main ram.

Describing our invention in detail, the press comprises a frame member, generally designated 2, having intermediate its upper and lower extremities an annular support web 4 adapted to support the press upon a foundation fragmentarily indicated at 6. At opposite sides thereof the member 2 is provided with spaced jaws or brackets 8 and 10 affording pivotal connection by means of pins 12 and 14, respectively, to the spaced arms 16 and 18 of the cover link, generally designated 20, said link comprising a cross piece 22 extending between the arms 16 and 18 and pivoted thereto adjacent the upper extremities thereof by means of trunnions 25, 25.

A forming or material cylinder 34 is secured to the member 2 by means of a plurality of tension rods or bolts, one of which is indicated at 36

2

(Figure 1), and a cover 42 is provided for the cylinder 34, said cover being pivotally connected by means of a pin 46 to a lug 48 on the cross piece 22 of the link 20, said lug having an arcuate surface in thrust engagement at 50 (Figure 1) with a complementary bushing or shoe 51 secured in the top of the cover 42. The cover 42 is connected to the cylinder 34 and is opened and closed by means of the link 20 as shown and described in detail in said copending application. It will be understood that, if desired, shims may be utilized at 52 (Figure 1) to adjust the height of the forming or material cylinder 34, thus creating any desired initial tension between said cylinder and the cover 42 as the latter is urged to closed position.

Integrally formed within the frame member 2 is a main ram cylinder 58 within which the main ram or piston 60 is reciprocal by means of hydraulic fluid, such as oil, supplied to said cylinder 58 by means of advance and pull-back pipes 61a and 61b, respectively, adapted to be connected through a valve casing 63 to a supply line 65 and a relief or exhaust line 67, a valve element 69 being rotatable within the casing 63 so as to place either of the pipes 61a or 61b in communication with the supply line 65 and to simultaneously place the other pipe in communication with the relief line 67. It will be understood that the valve 63, 69 is diagrammatically illustrated inasmuch as it is a conventional structure. The head 62 of the ram 60 is thus reciprocated within the liner 64 secured in any convenient manner within the material cylinder 34, to compress into a slug or brick therewithin the associated material which is inserted into the top of the material cylinder 34 in the manner hereinafter described.

Our invention comprises novel hydraulic means for adjustably controlling the stroke of the ram 60. To achieve this control, an auxiliary cylinder 66 is mounted by spaced bolts 68, 68 on the lower end or head 72 of the main ram cylinder 58, and an auxiliary ram 70 is reciprocal within the auxiliary cylinder 66, the upper end of said ram 70 extending through the head 72 of the main ram cylinder 58 for engagement at 74 with the lower end of the main ram 60. Pressure fluid, such as oil, is supplied to the auxiliary cylinder 66 by means of a supply pipe 76 equipped with a suitable shut-off valve 78.

It may be noted that suitable packing means 80 is provided to prevent escape of actuating fluid from the upper end of the main cylinder 58, and, likewise, suitable packing means 82 is provided 55 to prevent escape of the actuating fluid from the

lower end of the main cylinder 58. Suitable packing means 84 is also provided to prevent escape of actuating fluid from the upper end of the auxiliary cylinder 66.

In operating our novel press, the cover 42 is moved to open position by means of the link 20, and fluid is then admitted to the auxiliary cylinder 66 through the valve 78 and the pipe 76 until the main ram 60 is moved upwardly by the auxiliary ram 70 to a predetermined initial position within the material cylinder 34, thus predetermining the amount of material which may be inserted or poured into the top of the material cylinder. The lowest initial position of the main ram 60 is illustrated in solid lines in Figure 1, and the highest possible initial position is illustrated in dot and dash lines in said figure.

When the main ram 60 has assumed the desired position within the press cylinder 34, the valve 78 is closed. The material to be compressed is then inserted or poured into the top of the material cylinder 34, and thereafter the cover is urged to closed position as illustrated in Figure 1. Pressure fluid is then admitted to the main ram cylinder to urge the main ram upwardly, thus compressing the material within the material cylinder 34.

As will be apparent, any suitable means may be provided, if desired, to evacuate air from the forming or material cylinder, prior to the compressing operation; however, such means is no part of the present invention and is therefore not illustrated.

After the material within the material cylinder 34 has been compressed to the desired compactness, the main ram 60 is moved downwardly by means of actuating fluid in the main ram cylinder 58 to release the pressure against the slug and the cover 42, and thereafter the cover is opened and the slug is ejected from the upper end of the press cylinder by the ram 60. The main ram 60 is then urged to its lowest and predetermined position against the upper end of the auxiliary ram 70, and the press is ready for another cycle.

Pressure on the main ram 60 as it is urged to closed position never exceeds the pressure on the auxiliary ram 70, as will be readily understood.

It is to be understood that we do not wish to be limited by the exact embodiment of the device shown which is merely by way of illustration and not limitation as various and other forms of the device will, of course, be apparent to those skilled in the art without departing from the spirit of the invention or the scope of the claims.

We claim:

1. In an hydraulic press, a material cylinder open at its lower end, a cover for opening and closing the upper end of said cylinder, a main ram cylinder therebeneath, a vertical ram within said main cylinder, a source of hydraulic pressure fluid connected to said ram cylinder for reciprocating said ram within both of said cylinders, an auxiliary ram cylinder beneath said main cylinder and sealed at all times against communication therewith, an auxiliary ram within said auxiliary cylinder positioned to abut with the lower end of said main ram, and a source of hydraulic pressure fluid connected to said auxiliary cylinder for moving said auxiliary ram upwardly to a predetermined position for limiting the stroke of said main ram.

2. In an hydraulic press, a material cylinder open at one end thereof, a cover for opening and closing the opposite end thereof, a main ram having a head at one end thereof received within said cylinder, a main ram cylinder receiving the oppo-

site end of said ram, a source of hydraulic pressure fluid connected to said main cylinder for reciprocating said ram within both of said cylinders, an auxiliary ram cylinder having a relatively small diameter with respect to that of said main cylinder, an auxiliary ram within said auxiliary cylinder and positioned to abut with said main ram, and hydraulic fluid means within said auxiliary cylinder for advancing said auxiliary ram to a predetermined position for limiting the stroke of said main ram, said main and auxiliary cylinders being at all times closed against communication with respect to each other.

3. In an hydraulic press of the class described, a material cylinder, means for closing one end thereof, a ram having a head on one end thereof reciprocal within the opposite end of said cylinder, hydraulic motor means for reciprocating said ram, a relatively small diameter auxiliary ram positioned to abut with the opposite end of said main ram, and hydraulic motor means independent of said first-mentioned means for urging said auxiliary ram against said main ram in the direction axially thereof and thereby moving said head to a predetermined point within said cylinder for predetermining the amount of material which may be inserted within the first-mentioned end thereof.

4. In an hydraulic press of the class described, a material cylinder, means for closing one end thereof, a ram having a head on one end thereof reciprocal within the opposite end of said cylinder, hydraulic motor means for reciprocating said ram, a relatively small diameter pistonlike member positioned to abut with the opposite end of said ram, and means at all times independent of said motor means for moving said member toward said material cylinder and thereby moving said head to a predetermined point within said cylinder for predetermining the amount of material which may be inserted within said first-mentioned end thereof.

5. In an hydraulic press of the class described, a material cylinder, a main ram having a head at one end thereof received within said cylinder, a main ram cylinder receiving the opposite end of said main ram, a source of pressure fluid connected to said main cylinder for reciprocating said ram within both of said cylinders, a relatively small diameter auxiliary ram cylinder, an auxiliary ram within said auxiliary cylinder positioned to abut with said main ram and separable therefrom, and hydraulic fluid means within said auxiliary cylinder for advancing said auxiliary ram to a predetermined position, thereby limiting the stroke of said main ram within said material cylinder, said main and auxiliary cylinders being at all times sealed against intercommunication.

6. In an hydraulic press of the class described, a material cylinder open at one end thereof, a cover for opening and closing the opposite end thereof, a main ram having a head at one end thereof received within said cylinder, a main ram cylinder receiving the opposite end of said ram, hydraulic fluid means in said main cylinder for reciprocating said ram within both of said cylinders, a relatively small diameter pistonlike member extending into said cylinder and positioned to abut said opposite end, and means entirely independent of said first-mentioned means for advancing said member into said ram cylinder axially thereof, thereby limiting the stroke of said ram.

7. In an hydraulic press, a main ram cylinder, a main ram therewithin, hydraulic fluid means

for reciprocating said ram within said cylinder, a relatively small diameter auxiliary cylinder spaced from said first-mentioned cylinder, an auxiliary ram in said auxiliary cylinder, hydraulic fluid means for reciprocating said auxiliary ram within said auxiliary cylinder, the adjacent ends of the respective rams being positioned to abut with each other, whereby the stroke of said main ram is limited by the position of said auxiliary ram, said main and auxiliary cylinders being at all times closed against intercommunication.

8. In an hydraulic press of the class described, a material cylinder open at one end thereof, a cover for opening and closing the opposite end thereof, a ram having a head at one end thereof received within said cylinder, a ram cylinder receiving the opposite end of said ram, hydraulic fluid means in said ram cylinder for reciprocating said ram within both of said cylinders, and an auxiliary hydraulic device entirely independent of said means and operatively connectable to said main ram for limiting the length of its stroke within said ram cylinder.

9. In an hydraulic press of the class described, a material cylinder, a ram having a head on one end thereof reciprocal within said cylinder, hydraulic motor means for reciprocating said ram, a relatively small diameter auxiliary ram positioned to abut with the opposite end of said main ram, and hydraulic motor means entirely independent of said first-mentioned means for urging said auxiliary ram against said main ram and

thereby moving said head to a predetermined point within said cylinder.

10. In an hydraulic press, a cylinder open at both ends thereof, a cover for closing one end of said cylinder, a ram reciprocal within the opposite end of said cylinder, means for reciprocating said ram, and an auxiliary hydraulic device independent of said means and including a ram member engageable with said first-mentioned ram for adjustably controlling the stroke thereof.

11. In an hydraulic press, a main ram cylinder, a substantially vertical main ram reciprocal therewithin, an auxiliary ram cylinder, an auxiliary ram in said auxiliary cylinder, the upper end of said last-mentioned ram being positioned to bear against the lower end of said main ram for limiting the stroke thereof, and a source of pressure fluid connected to each cylinder independently of the other for actuating the associated ram.

12. In an hydraulic press, a main ram cylinder, a main ram reciprocal therewithin, an auxiliary ram cylinder, an auxiliary ram in said auxiliary cylinder, said last-mentioned ram being positioned to bear against said main ram for controlling the stroke thereof, and means for actuating each ram independently of the other ram comprising a source of pressure fluid connected to each cylinder, each of said cylinders being at all times closed from communication with the other cylinder.
